UNITED STATES PATENT OFFICE.

WILLIAM STEPHEN BOYCE, OF COLUMBUS, OHIO, ASSIGNOR TO THE RAIL JOINT COMPANY, OF NEW YORK, N. Y., A CORPORATION OF NEW YORK.

INSULATED RAIL-JOINT.

1,361,816.

Specification of Letters Patent. Patented Dec. 14, 1920.

Application filed October 6, 1919. Serial No. 328,684.

To all whom it may concern:

Be it known that I, WILLIAM S. BOYCE, citizen of the United States, residing at Columbus (33 So. Washington Street,) in the 5 county of Franklin and State of Ohio, have invented certain new and useful Improvements in Insulated Rail-Joints, of which the following is a specification.

This invention relates to an improvement 10 in insulated rail joints providing a novel base construction possessing practical utility in its application to joints of the type having a metal shoe angles and wooden fillers.

A primary object of the invention is to 15 provide an insulated rail joint having a strong and substantial metal base support for the rails while at the same time maintaining an effectual and economical insulation of the joint. At the same time the invention has in view a construction which 20 is intended to better adapt the shoe angle type of joint to successfully meet the heavy demands and requirements of modern traffic conditions and to otherwise materially enhance the serviceability of the joint, in 25 forms of construction especially where the wooden filler occupies the fishing space of the rail and underlies the head of the rail.

Accordingly, the distinctive feature of 30 the invention resides in the employment of a base plate of novel formation and so combined with the base members of the shoe angles and the insulation as primarily to provide means whereby the rail ends are 35 substantially and uniformly supported and the pressure brought upon the base fiber or insulation is uniformly distributed, thereby preventing early breaking out of the fiber and better maintaining full insulating 40 function of the joint.

Another important object in view is to 45 provide a base construction for an insulated joint which insures a solid and substantial metal rail base support over the ties between the base members of the opposite steel shoes, thus obtaining a uniform support for the rail ends and also a uniform and full seating 50 of the joint on the tie.

A further object of the invention is to 55 provide an improvement in the base construction of the shoe angle type of joint wherein unequal pressure on the base fiber is eliminated regardless of the poor fitting of

the shoes and which will also prevent cutting of the base fiber between the base plate 55 and the outer edges of the rail base flanges.

With these and other objects in view which will more readily appear as the nature of the invention is better understood the same consists in the novel construction, 60 combination and arrangement of parts hereinafter more fully described, illustrated and claimed.

The fundamental feature of the invention, which centers in the novel base plate construction and its coöperation with the shoe angles and the base fiber, is necessarily susceptible of embodiment in modified forms without departing from the invention or sacrificing any of the advantages thereof 70 but certain preferred and practical embodiments are illustrated in the accompanying drawings; in which:

Figure 1 is a sectional view of an insulated rail joint embodying one form of the 75 invention wherein the base fiber is formed with an up-turned guard flange interposed between one rail flange and the up-right member of one shoe to prevent contact between these opposing metallic surfaces.

Fig. 2 is a view similar to Fig. 1 illustrating a modified arrangement of the insulation wherein a separate side plate of insulation is clamped between one shoe angle and one filler block, and coöperates with the 85 base fiber or base sheet of insulation to provide the necessary insulation.

Fig. 3 is a side elevation of the rail joint with the shoe angle removed to better expose the structural formation of the novel 90 base plate.

Fig. 4 is a bottom plan view of the base plate.

Like references designate corresponding parts in the several figures of the drawings.

As indicated, the invention in its preferable application has special utility when associated with a rail joint structure including a wooden filler block fitting the fishing space 100 of the rail, and a steel shoe angle having a direct clamping engagement with the outer side of the filler block, but it is not necessarily limited to such application. Nevertheless, in order that the essential and distinctive features of the invention may best

be understood the several suggested embodiments thereof shown in the drawings are illustrated in connection with a rail joint structure including in combination with the rails R and the usual joint bolts 1 the wooden filler blocks 2 and the steel shoe angles 3. These principal elements are present in all forms of the invention illustrated, and it will be observed that each of the opposite shoe angles 3 comprises the upright bolting member 4 and the horizontal integrally extending base member 5. Also each shoe angle, being designed to clampingly engage the outer side of the filler block, is preferably formed at its inner side with an inclined clamping face 4^a coöperating with a correspondingly inclined bearing face 2^a upon the outer side of the adjacent filler block, and upon its outer side the upright member of each shoe angle is formed with a vertical bolting face 4^b against which the heads or nuts of the bolts are clamped to provide for drawing the shoe angle inwardly into proper fit and engagement with the wooden filler block. The form of construction described has been found effective and reliable in service under ordinary conditions, and as above pointed out it is proposed by the present invention to better adapt such a joint to successfully meet the exacting requirements of modern traffic conditions, while at the same time preserving to a marked degree the fiber insulation.

In the attainment of that principal object of the invention there is employed a base plate 6 of special construction. This base plate is intended to occupy an operative position between the bottom of the rails and the upper sides of the base members 5 of the opposite shoes, and also to have a direct supporting engagement with the tie. These functions are made possible by designing this base plate 6 in such a manner that it is formed with a relatively thick and heavy central block portion 7 extending the full length of the base plate body and of such depth vertically as to occupy the space between the under sides of the bottoms of the rails and the surface of the tie, and therefore lying in the interval or opening between the inner edges of the base members 5 of the opposite shoe angles, as may be best seen from Figs. 1 and 2 of the drawings. In addition to the relatively thick and central block portion 7 of the base plate, the base plate body is formed with the lateral supporting flanges 8 which project from the sides of the central block portion 7 and extend beneath the rail base flanges over the base members 5 of the shoe angles. Furthermore, at the ends of the longitudinally extending lateral supporting flanges 8 the base plate body is provided with depending holding lips or hooks 9 which overlap and engage with the ends of

the base members 5 of the opposite shoe angles. This detail of the base plate is of practical importance since it provides means for positively holding the base plate correctly in its operative position under the rail ends and prevents shifting thereof in any direction tending to displace it or tending to place undue friction on the insulation held between the base plate and the rail ends.

A further feature of the novel base plate construction, which is useful in an insulated rail joint, is that of beveling off the top edge portions of the base plate body as at 10 to provide well defined clearance spaces 80 11 between the side edges of the base plate and the portions of the base insulation underlying the edges of the rail flanges, thereby preventing the cutting of the base fiber between the base plate and the outer edges 85 of the rail base flanges, and assuring uniform and equal distribution of the pressure which is brought to bear upon the base fiber.

The insulation of a rail joint having the novel base construction described includes the usual insulating end post and the usual bolt insulation. In addition to that insulation the present invention contemplates the use of a sheet of base insulation 12 extending entirely across and beneath the rail ends and interposed between the rail bottoms and the upper side of the base plate 6. In the adaptation shown in Fig. 1 of the drawings the said sheet of base insulation 12 is formed with a side plate of insulation 13 which is held clamped between the upright member 4 of one shoe and the adjacent filler block 2, and the opposite edge portion of said sheet of base insulation 12 is formed with a short upstanding guard flange 14 which lies in the space between the edge of one rail flange and the upright member 4 of the opposite shoe, thus preventing any metallic contact in that location. Should it be desired to provide for a more effective insulation there may be employed a separate side plate of insulation 15 clamped between the upright member of one shoe angle and the adjacent filler block and provided at its lower edge with a guard apron extension 16 which lies between an exposed part of the upright member of one shoe angle and one rail flange. In this latter modification of the invention, illustrated in Fig. 2 of the drawings the guard flange 14 is omitted from one edge of the sheet of base insulation 12.

From the foregoing it is thought that the construction, functioning and many advantages of the herein described improvement in insulated rail joints will be readily apparent to those familiar with the art and it will be understood that changes in the form, proportion and minor details of construc-

tion as fall within the scope of the appended claims may be resorted to without departing from the scope of the present invention.

I claim:—

5. 1. A rail joint including opposite shoe angles, and a base plate overlying the base members of the shoes and provided at its top edge portions with insulation clearance faces disposed beneath the edges of the rail flanges, and an insulation sheet interposed 10 between the rail bottom and the base plate.

15. 2. A rail joint including opposite shoe angles, a base plate overlying the base members of the shoes and interlocked therewith, said base plate being provided at its top edge portions with insulation clearance faces disposed beneath the edges of the rail flanges, and an insulation sheet interposed 20 between the rail bottom and the base plate.

25. 3. A rail joint including opposite shoe angles, a base plate having a relatively thick tie engaging block portion disposed beneath the base members of the shoes and also having members overlying and interlocked with the base members of the shoes, said base plate being further provided at its top edge portions with insulation clearance faces disposed beneath the edge of the rail flange,

and an insulation sheet interposed between 30 the rail bottoms and the base plate.

4. A rail joint including the opposite shoe angles, fillers interposed between the upright members of the shoes and the rails, a base plate, an insulation sheet interposed between the base plate and the rail bottoms and formed with a member clamped between one filler and shoe angle, said insulation sheet being provided at one edge with an upturned guard flange for the edge of 40 one rail flange.

5. A rail joint including in combination with the rails the opposite shoe angles, having base members provided with flat horizontal upper faces and lower flat tie engaging faces, a base plate provided with a central tie engaging block portion disposed between the opposite base members of the shoe, and flat horizontal supporting flanges engaging the horizontal upper faces of said 45 base members and having an interlocked engagement with said base members.

In testimony whereof I hereunto affix my signature in the presence of two witnesses.
